UNITED STATES PATENT OFFICE

169,007

PORTABLE FAN

Caryl A. Lindberg, Glendale, and John M. Repp,
St. Louis, Mo., assignors to The Emerson Electric
Manufacturing Company, St. Louis, Mo., a
corporation of Missouri

Application August 9, 1952, Serial No. 20,962

Term of patent 14 years

(Cl. D26—7)

To all whom it may concern:

Be it known that we, Caryl A. Lindberg and John M. Repp, citizens of the United States, residing at Glendale and St. Louis, both in the State of Missouri, have invented a new, original, and ornamental Design for a Portable Fan, of which the following is a specification, reference being had to the accompanying drawing, forming a part hereof.

Fig. 1 is a front elevation of the portable fan, showing our new design; and

Fig. 2 is a side elevation.

We claim:

The ornamental design for a portable fan, as shown.

CARYL A. LINDBERG.
JOHN M. REPP.
